United States Patent Office

Des. 187,384
Patented Mar. 8, 1960

187,384

DETACHABLE FLASHLIGHT HEAD UNIT

Richard E. Hagen, Madison, Wis., assignor, by mesne assignments, to The Electric Storage Battery Company, Philadelphia, Pa., a corporation of New Jersey

Application March 22, 1957, Serial No. 45,404

Term of patent 14 years

(Cl. D48—24)

Fig. 1

Fig. 2

Fig. 3

Fig. 4

Figure 1 is a perspective view of a detachable flashlight head unit embodying my new design;

Figure 2 is a top view thereof;

Figure 3 is a front view thereof; and

Figure 4 is a rear view thereof.

The dominant features of my design reside in the portions shown in full lines. The battery has been omitted in Figs. 1 and 4 for convenience of illustration only.

I claim:

The ornamental design for a detachable flashlight head unit, as shown and described.
